DESIGN FOR A SHOE

George Codish, New York, N. Y., assignor to Jonas A. Senter, Brooklyn, N. Y.

Application April 28, 1943, Serial No. 110,068

Term of patent 3½ years

To all whom it may concern:

Be it known that I, George Codish, a citizen of the United States, residing at 2710 Sedgwick Avenue, New York city, county of Bronx, State of New York, have invented a new, original, and ornamental Design for a Shoe, of which the following is a specification, reference being had to the accompanying drawing, forming a part thereof.

Fig. 1 is a side view of a shoe showing my new design; and

Fig. 2 is a bottom plan view of the shoe shown in Fig. 1.

The essential features of my design for a shoe reside in the sole portion shown in full lines and comprising the combination of the strands of rope covering the entire sole and heel portions, except for a substantially elliptical, plain, smooth portion in the ball portion of the sole, all as shown.

I claim:

The ornamental design for a shoe, as shown and described.

GEORGE CODISH.
